UNITED STATES PATENT OFFICE

EDWARD N. JACOBI, OF MILWAUKEE, WISCONSIN, ASSIGNOR TO BRIGGS & STRATTON CORPORATION, OF MILWAUKEE, WISCONSIN, A CORPORATION OF DELAWARE

LOCK

Application filed February 1, 1929. Serial No. 336,715.

This invention relates to certain new and useful improvements in locks and refers more particularly to that type of lock in which the retraction of the locking bolt, frees the 5 mounting head for longitudinal movement, means being provided for guiding and limiting such movement.

Heretofore, the means for guiding and limiting the movement of the mounting head had 10 numerous objections, principal of which was the possibility of the screw becoming loosened and thus permitting detachment of the mounting head from its casing, and the additional time required in assembling and dis- 15 assembling for purposes of repair.

With these and other objections in mind, this invention has as one of its objects the provision of improved means for guiding and limiting the longitudinal movement of the 20 mounting head of locks of the character described, which automatically becomes operative upon the insertion of the mounting head in its casing.

Another object of this invention resides in 25 the provision of a lock of the character described in which the means for limiting and guiding the longitudinal movement of its mounting head is retained in operative position by the expansive spring provided to im- 30 part movement to the mounting head.

Another object of this invention resides in 35 the provision of a lock of the character described having means which, when in normal position, prevents the outward movement of the lock cylinder mounting head with 40 respect to its casing, and which may be readily moved to inactive position to permit detachment of the mounting head from its casing by merely depressing a portion thereof.

A further object of this invention is to 45 provide an improved means for limiting the longitudinal movement of a lock cylinder mounting head with respect to its casing, which consists of a plate member having an angular projection with means carried by the projection and received in recesses in the mounting head to maintain the same assembled with the mounting head and permit 50 rocking movement thereof to either project

its angularly directed portion beyond the periphery of the mounting head or to permit its movement within the periphery of the mounting head.

And a still further object of this invention 55 is to reduce the cost of manufacture by stamping the member which limits the longitudinal movement of the mounting head with respect to its casing, from bendable metal.

With the above and other objects in view 60 which will appear as the description proceeds, my invention resides in the novel construction, combination and arrangement of parts substantially as hereinafter described and 65 more particularly defined by the appended claims, it being understood that such changes in the precise embodiment of the hereindisclosed invention may be made as come within the scope of the claims.

In the accompanying drawing, I have illustrated one complete example of the physical embodiment of my invention constructed according to the best mode I have so far devised for the practical application of the 75 principles thereof, and in which:

Figure 1 is a view of a lock device embodying my invention with parts broken away and in section to illustrate structural details;

Figure 2 is a view partly in elevation, and partly in section, taken through Figure 1 on the plane of the line 2-2;

Figure 3 is a view similar to Figure 1 illustrating the manner in which the means for 85 limiting longitudinal movement may be moved to an inactive position, and

Figure 4 is a perspective view of the lock cylinder mounting head and the means for limiting longitudinal movement of the head 90 with respect to the casing.

Referring now more particularly to the accompanying drawing, in which like numerals designate like parts throughout the several views, the numeral 5 designates a tubular casing having a sleeve 6 extended from one end thereof to which the adjacent end of a flexible armoured cable 7 is secured. The cable 7 contains one or more conductor wires, not shown, which lead from a switch 100

(not shown) mounted in the casing, and having an actuating member 8 movable with a lock cylinder mounting head 9 mounted in the opposite end of the casing 5. The lock cylinder mounting head is yieldably urged outwardly of the casing by an expansive spring 10 confined between the inner end of the lock cylinder mounting head and a suitable stop member 11 within the casing, the mounting head being restrained against longitudinal movement by a locking bolt 12 which, when in locked position, extends beyond the periphery of the mounting head through a suitable opening 13 formed in the casing wall.

The locking bolt 12 forms part of a conventional lock structure including a lock cylinder 14 rotatable in the mounting head and having the usual tumblers, not shown, which, upon the insertion of a proper key 15 are movable to an inactive position to permit the rotation of the cylinder to actuate the locking bolt 12 to its unlocked position within the periphery of the mounting head. Thus it will be seen that when the key 15 is inserted and turned to retract the locking bolt to its unlocked position, the spring 10 moves the mounting head outwardly to effect the desired movement of the switch actuating member 8, the movement of the mounting head being guided and limited by the stop 16 of a novel stop member 17, and which is movable in an elongated slot 18 formed in the casing wall, said stop engaging the outer end of the slot when the head is in its outermost position, as illustrated in dotted lines in Figure 2.

The stop member is preferably formed of bendable metal and consists of a plate 19 having its ends shaped to conform to the diameter of the lock cylinder mounting head and having a member 20 of reduced width extended centrally from its upper edge, at an angle slightly greater than a right angle, the outer end of said member forming the stop 16. The stop member is mounted from the inner end of the cylinder mounting head by means of a pair of projections 21 extended from opposite sides of the member 20 at a medial point and received in recesses 22 formed in the mounting head and which communicate with a central recess 23 of equal depth and adapted to receive the member 20.

The inner end of the mounting head is cut away, as at 24, to provide an overhanging portion 25 through which the central recess 23 extends to a point flush with the cut away portion 24. The intersection of the vertical portion of the recess 23 which is flush with the cut away portion 24 and the horizontal portion of the recess is provided with an upwardly projected semi-circular boss 26 which provides a fulcrum about which the stop member is rockable, as will be readily apparent.

When the stop member is assembled with the mounting head in the manner described and the plate 19 thereof is flush against the cut away portion 22, the end 16 of its member 20, by reason of its angular position extends beyond the periphery of the mounting head, as clearly illustrated in Figure 1, and due to the interlocking action between the projections 21 and the recesses 22, detachment of the stop member from the mounting head may be accomplished only by lifting the member vertically out of the recesses 22 and 23.

In assembling, the mounting head with which the lock cylinder and stop member have been assembled, is inserted into the open end of the casing 5, the projecting end 16 of the stop member moving into the recess 23 until it aligns with the elongated opening 18 whereupon the action of the spring 10 which has been engaged by the plate 19 causes the stop member to rock about its fulcrum 26 and extend its end 16 upwardly beyond the periphery of the mounting head and into the slot 18. Continued movement of the mounting head aligns the locking bolt with its opening 13, which due to the action of its spring, not shown, snaps into place and locks the head against longitudinal movement.

It will be noted that the end 16 of the stop member not only limits outward longitudinal movement of the mounting head, but likewise maintains the same in proper transverse alignment with the casing to insure the alignment of the locking bolt with its opening 13.

When it is desired to remove the mounting head for purposes of repair or the like, it is only necessary to insert a convenient tool through the slot 18 and depress the end 16 of the stop member within the periphery of the mounting head as illustrated in Figure 3, when the tension of the spring 10 will quickly move the mounting head outwardly of the casing.

From the foregoing description, taken in connection with the accompanying drawing, it will be readily apparent to those skilled in the art to which an invention of the character described appertains, that I provide an improved manner of guiding and limiting the movement of a lock cylinder mounting head within its casing which incorporates means becoming active upon the assembly of the mounting head with its casing, and which is readily movable to a position permitting detachment of the mounting head from the casing.

I claim:

1. In a lock device including a casing, a lock cylinder mounting head longitudinally movable in the casing, and means urging the lock cylinder mounting head in one direction, means carried by the lock cylinder mounting head and cooperating with the casing for limiting movement of the mount-

ing head by said urging means, and means permitting the ready movement of said last mentioned means to an inactive position to permit detachment of the lock cylinder mounting head from the casing.

5 2. In a lock device including a casing and a lock cylinder mounting head longitudinally movable in the casing, means carried by the mounting head and cooperating with the casing for limiting the longitudinal movement of the mounting head with respect to the casing, and means whereby said last mentioned means becomes active upon the assembly of the lock cylinder mounting head with the casing.

10 3. In a lock device including a casing and a lock cylinder mounting head longitudinally movable in the casing, a member carried by the mounting head and adapted to limit the longitudinal movement of the mounting head in one direction with respect to the casing, and means mounting said member for movement to and from an active position.

15 4. In a lock device including a casing and a lock cylinder mounting head longitudinally movable in the casing, a member carried by the lock cylinder mounting head and cooperating with the casing to limit the longitudinal movement of the lock cylinder mounting head with respect to the casing, means whereby said member is movable to and from an active position, and means whereby said member assumes an active position upon the assembly of the lock cylinder mounting head with the casing.

20 5. In a lock device of the character described including a casing and a lock cylinder mounting head longitudinally movable in the casing, a stop member carried by the lock cylinder mounting head and cooperating with the casing to limit longitudinal movement of the lock cylinder mounting head with respect to the casing, means permitting movement of said stop member to and from active position whereby said stop member assumes an active position upon assembly of the lock cylinder mounting head with the casing, and said stop member being readily movable to an inactive position to permit detachment of the lock cylinder mounting head from the casing.

25 6. In a lock device of the character described including a casing, a lock cylinder mounting head longitudinally movable in the casing, means normally urging said lock cylinder mounting head outwardly of the casing, a stop member carried by the lock cylinder mounting head and cooperating with the casing for limiting the movement of

30 the lock cylinder mounting head by said urging means, means permitting movement of the stop member to and from active position, and means whereby said urging means maintains the stop member in an active position.

35 7. In a lock device of the character de-

scribed including a casing and a lock cylinder mounting head movable in the casing, means urging the lock cylinder mounting head in one direction in the casing, a member carried by the lock cylinder mounting head and cooperating with the casing for guiding and limiting the movement of the lock cylinder mounting head in the casing by said urging means, means permitting movement of said member to and from an active position, and means whereby said urging means yieldably retains said member in an active position.

40 8. In a lock device of the character described including a casing and a lock cylinder mounting head movable in the casing, a member readily detachably carried by the lock cylinder mounting head and cooperating with the casing for guiding and limiting the movement of the lock cylinder mounting head in the casing, said member being movable to and from an active position, and means whereby said member is normally in active position.

45 9. In a lock device of the character described including a casing and a lock cylinder mounting head longitudinally movable in the casing, a stop member carried by the lock cylinder mounting head and cooperating with the casing to guide and limit longitudinal movement of the lock cylinder mounting head with respect to the casing, means formed on the lock cylinder mounting head and about which the stop member is rockable to and from active position, and interlocking means carried by the lock cylinder mounting head and the stop member whereby detachment of the stop member from the lock cylinder mounting head is prevented as long as the lock cylinder mounting head is assembled with the casing.

50 10. In a lock device of the character described including a casing and a lock cylinder mounting head longitudinally movable in the casing, a stop member carried by the lock cylinder mounting head and cooperating with the casing to guide and limit longitudinal movement of the lock cylinder mounting head with respect to the casing, means formed on the lock cylinder mounting head to provide a fulcrum about which the stop member is rockable to and from active position, lugs formed on the stop member and engageable in recesses formed in the lock cylinder mounting head for maintaining the stop member assembled with the lock cylinder mounting head, and means carried by the stop member which when moved towards the lock cylinder mounting head moves the stop member into active position.

55 11. In a lock device of the character described including a casing and a lock cylinder mounting head longitudinally movable in the casing, a stop member carried by the lock cylinder mounting head and cooperating with the casing to guide and limit lon-

- 5 gitudinal movement of the lock cylinder mounting head with respect to the casing, the lock cylinder mounting head having a recess adapted to receive the stop member, fulcrum means adjacent said recess and about which the stop member is rockable into and out of the recess to position the same in either inactive or active position, lugs formed on the stop member and engageable in recesses extended from said recess in the lock cylinder mounting head for preventing longitudinal movement of the stop member with respect to the mounting head, and means carried by the stop member which when moved toward the lock cylinder mounting head rocks the stop member about the fulcrum means to move the stop member out of the lock cylinder mounting head recess and project the same into active position.
- 10 12. In a lock device including a casing, a lock cylinder mounting head longitudinally movable in the casing, a member carried by the mounting head and cooperating with the casing for limiting and guiding the longitudinal movement of the mounting head with respect to the casing, and means for yieldably maintaining the member in operative position.
- 15 13. In testimony whereof I have hereunto affixed my signature.
